ENGINE

William L. Brown, 3rd, and William L.
Brown, 4th, Philadelphia, Pa.

Application November 27, 1946, Serial No. 712,524

4 Claims. (Cl. 121—124)

1

This invention relates to engines, and more particularly to engines which may be built in small sizes to serve as the power plants of model airplanes and the like.

It is the principal object of the present invention to provide an engine capable of being operated by gas under pressure, stored in liquefied or compressed form, and in which adjustment of the speed of operation may be effected as desired.

It is a further object of the present invention to provide an engine capable of operating on gas under pressure, such as carbon dioxide, stored in liquefied or compressed form.

It is a further object of the present invention to provide, in an engine of the character aforesaid, an improved admission valve and actuation thereof.

It is a further object of the present invention to provide, in an engine of the character aforesaid, adequate provisions for lubrication.

Other objects and advantageous features of the invention will be apparent from the specification and claims.

The nature and characteristic features of the invention will be more readily understood from the following description, taken in connection with the accompanying drawings forming part hereof, in which:

Figure 1 is a view partly in elevation and partly in vertical section showing a preferred embodiment of an engine in accordance with the present invention;

Fig. 2 is a vertical sectional view taken approximately on the line 2—2 of Fig. 1; and

Fig. 3 is a horizontal sectional view taken approximately on the line 3—3 of Fig. 1.

It should, of course, be understood that the description and drawings herein are illustrative merely, and that various modifications and changes may be made in the structure disclosed without departing from the spirit of the invention.

Referring more particularly to the drawings, the engine, in accordance with the present invention, preferably includes a crank case 10 preferably formed as a one piece die casting having one or more outstanding lugs 11 through which bolts 12 are adapted to extend for mounting the engine in position in the fuselage of a model airplane, or in any other desired location.

The crank case 10 preferably has a closure plate 13 at one side thereof which may be secured in position in any desired manner. The opposite side of the crank case 10 preferably has a bearing 14 formed therein within which a crank

shaft 15 is mounted for rotation. The outer end of the crank shaft 15, beyond the bearing 14, may be of reduced diameter, as at 16, for the reception of clamping discs 17 and 18, and the outer end may also be threaded, as at 19, for the reception of a nut 20 for the purpose of securing a propeller (not shown) or other driven member on the outer end of the crank shaft 15, between the discs 17 and 18.

The inner end of the crank shaft 15, within the crank case 10, is provided with a cylindrical crank disc 21 which serves to position the crank shaft 15 with respect to the bearing 14, and which has mounted therein a crank pin 22.

15 The upper part of the crank case 10 has an upwardly extending boss or projection 23, provided with an internally threaded portion 24 for the reception of the lower externally threaded end 25 of a cylinder 26. The cylinder 26 is also preferably formed in one piece.

15 The exterior of the cylinder 26 may be provided with fins 27 for heat absorption to prevent undue cooling of the engine upon expansion of the compressed gas, and to prevent condensation of gas or moisture upon expansion of the gas during operation.

25 The cylinder 26 is adjustable with respect to the crank case 10 by the engagement of the threaded portions 24 and 25, and is held in adjusted position by a lock nut 28 in engagement with the threaded portion 25 of the cylinder 26 and with the upper end of the boss or projection 23. Adjacent the lower end of the cylinder 26, a plurality of exhaust ports 29 is provided, in communication with the interior of the cylinder 26 and with the atmosphere, and functioning as hereinafter explained.

35 The cylinder 26 is provided with an upwardly extending internally threaded portion 30 for the reception of an externally threaded cylinder head 31, and a washer 32 of resilient material is interposed between the cylinder head 31 and extension 30 at the upper end of the cylinder 26 for preventing fluid leakage. The cylinder head 31 is provided with a compressed gas delivery tube 33 for the delivery of gas under pressure for operating the engine, as hereinafter explained, and, if desired, the tube 33 may be of small internal bore to provide a restriction between the source of pressure fluid (not shown) and the engine to permit of partial expansion of the operating pressure fluid prior to its delivery to the engine. The tube 33 is adapted to extend inwardly, as at 34, and to serve as a stop, as herein-40 after explained.

45 The crank case 10 preferably has a closure plate 13 at one side thereof which may be secured in position in any desired manner. The opposite side of the crank case 10 preferably has a bearing 14 formed therein within which a crank

50 shaft 15 is mounted for rotation. The outer end of the crank shaft 15, beyond the bearing 14, may be of reduced diameter, as at 16, for the reception of clamping discs 17 and 18, and the outer end may also be threaded, as at 19, for the reception of a nut 20 for the purpose of securing a propeller (not shown) or other driven member on the outer end of the crank shaft 15, between the discs 17 and 18.

Spaced downwardly from the upper end of the cylinder 26, a transversely extending wall 35 is provided which separates the space within the cylinder and below the cylinder head 31 into a fluid delivery and valve chamber 36 and a working chamber 37. The wall 35 preferably has a central opening 38 therethrough, with a portion of conical shape to provide a valve seat 39 and to permit the seating thereon of a spherical ball 40. The ball 40 serves as an admission or inlet valve for the working chamber 37.

In the interior of the cylinder 26 and in the working chamber 37 below the transverse wall 35 a piston 41 is provided for reciprocation and for controlling the exhaust ports 29. The piston 41 has a wrist pin 42 therein which is connected by a connecting rod 43 to the crank pin 22. On the upper face of the piston 41 a push rod or abutment 44 is provided for moving the ball 40 from its seat 39 to admit fluid from the chamber 36 for expansion in the chamber 37, as hereinafter explained.

With the piston 41 in a position with the push rod 44 out of engagement with the ball 40 and with gaseous fluid under pressure supplied to the pipe 33 and through the pipe 33 to the chamber 36, the engine is ready to be operated.

The shaft 15 is turned sharply by hand, such as by movement of the propeller, if a propeller is employed, and in the direction of rotation desired. The upward movement of the piston 41 causes the push rod 44 to engage the ball 40 and lift the same from its seat 39, permitting fluid under pressure from the chamber 36 to pass to the chamber 37 above the head of the piston 41. The lower end 34 of the pipe 33 acts as a stop and prevents displacement of the ball 40. As the piston 41 moves downwardly, the ball 40, by reason of its weight and the removal of the push rod 44, is permitted to rest on the seat 39 and cut off further delivery of fluid to the chamber 37. The pressure of the fluid in the chamber 36 also aids in seating the ball 40.

The fluid thus delivered to the working chamber 37 then expands and the piston 41 is moved downwardly by the expansion to a position to open the exhaust ports 29 and permit the discharge of the expanded gas to the atmosphere. As the piston 41 again moves upwardly, the push rod 44 again strikes the ball 40 and moves the same from its seat 39 to permit the delivery of gas under pressure from the chamber 36 to the chamber 37, the ball 40 again seating as before upon downward movement of the piston 41. The operation of the engine will continue so long as fluid is supplied through the pipe 33.

The chamber 36, particularly if the delivery pipe 33 has a restricted bore, functions not only as a valve chamber, but also as a storage chamber for pressure fluid and tends to eliminate fluctuations of pressure of the fluid admitted to the working chamber 37.

If it is desired to lubricate the engine, the oiling may be readily effected through the exhaust ports 29 when the piston 41 is at the top and at the bottom of its stroke, respectively.

If it is desired to adjust the actuation of the valve 40 to vary the speed, the lock nut 28 is loosened and the cylinder 26 turned slightly with respect to the crank case 10. If the cylinder 26 is moved downwardly with respect to the crank case 10, the length of the period of admission of gas is increased and the speed is increased, and if the cylinder 26 is moved upwardly with respect to the crank case 10, the length of the period of

admission of gas is decreased and the speed of the engine is decreased. The cylinder 26 can be locked at the desired position of adjustment with respect to the crank case 10 by tightening the lock nut 28.

We claim:

1. In an engine, a crank case having a crank rotatably mounted therein, a cylinder, a partition member in said cylinder separating the interior of said cylinder into a valve chamber and a working chamber, means for delivering pressure fluid to said valve chamber, said partition member being provided with an opening therethrough having a valve seat, a valve member for engagement with said seat, a piston connected to said crank and reciprocable with a fixed stroke in said working chamber, said cylinder having exhaust ports at one end thereof controlled by the movement of said piston, an abutment carried by said piston movable into and through said opening to engage said valve and move it from its seat to admit pressure fluid to said working chamber for actuating said piston, and means for adjusting the extent of opening of said valve member comprising an adjustable connection between said cylinder and said crank case.

2. In an engine, a crank case having a crank rotatably mounted therein, a cylinder, a partition member in said cylinder separating the interior of said cylinder into a valve chamber and a working chamber, means for delivering pressure fluid to said valve chamber, said partition member being provided with an opening therethrough having a valve seat, a valve member for engagement with said seat, a piston connected to said crank and reciprocable with a fixed stroke in said working chamber, said cylinder having exhaust ports at one end thereof controlled by the movement of said piston, an abutment carried by said piston movable into and through said opening to engage said valve and move it from its seat to admit pressure fluid to said working chamber for actuating said piston, and means for adjusting the extent of opening of said valve member comprising a direct threaded connection between said cylinder and said crank case, whereby the cylinder may be longitudinally shifted to change the location of the valve seat.

3. In an engine, a crank case having a crank rotatably mounted therein, a cylinder, a partition member in said cylinder separating the interior of said cylinder into a valve chamber and a working chamber, means for delivering pressure fluid to said valve chamber, said partition being provided with an opening therethrough having a valve seat, a valve member for engagement with said seat, a piston connected to said crank and reciprocable with a fixed stroke in said working chamber, said cylinder having exhaust ports at one end thereof controlled by the movement of said piston, an abutment carried by said piston for directly engaging said valve to move it from its seat to admit pressure fluid to said working chamber for actuating said piston, and means for varying the extent of opening of said valve and controlling said admission of pressure fluid comprising a direct threaded connection between said cylinder and said crank case, and a locking member carried by said cylinder for locking said cylinder and said crank case in predetermined adjusted positions.

4. In an engine, a crank case having a crank rotatably mounted therein, a cylinder having a threaded portion in direct engagement with a threaded portion of said crank case, a partition

member in said cylinder separating the interior of said cylinder into a valve chamber and a working chamber, means for delivering pressure fluid to said valve chamber, said partition being provided with an opening therethrough having a valve seat, a valve member for engagement with said seat, a piston connected to said crank and reciprocable in said working chamber, said cylinder having exhaust ports at one end thereof controlled by the movement of said piston, an abutment carried by said piston directly engaging said valve to move it from its seat to admit pressure fluid to said working chamber for actuating said piston, the threaded engagement between said cylinder and said crank case permitting a longitudinal shift of the cylinder to vary the extent of opening of said valve, and a lock nut in engagement with one of said threaded portions for locking said cylinder and said crank case in adjusted positions.
